(57) **CLAIM**

The ornamental design for an air fryer, as shown and described.

DESCRIPTION

1. Air fryer
2. Air fryer
- 1.1: Front
- 1.2: Back
- 1.3: Left
- 1.4: Right
- 1.5: Top
- 1.6: Bottom
- 1.7: Perspective
- 2.1: Front
- 2.2: Back
- 2.3: Left
- 2.4: Right
- 2.5: Top
- 2.6: Bottom
- 2.7: Perspective

The shape of the claimed air fryer is cylindrical with a small top and a large bottom; The front-top of the air fryer is inclined and there is a circular button located in the middle of the inclined surface; There is a rectangular protrusion located in the upper position of the left and right side; The

(Continued)

handle is fixed on the front middle of the air fryer; There are four rounded rectangular protrusions at the bottom of the air fryer.

The broken lines shown in the figures depict portions of the air fryer that form no part of the claimed design. The shade lines shown in the figures are utilized to illustrate surface contours of the claimed design and do not depict surface ornamentation.
